United States Patent Office.

WILLIAM H. McCOY AND A. WHEELER, OF CHARLESTOWN, MASSACHUSETTS.

Letters Patent No. 70,238, dated October 29, 1867.

IMPROVEMENT IN METALLIC GARTERS.

The Schedule referred to in these Letters Patent and making part of the same.

TO ALL WHOM IT MAY CONCERN:

Be it known that we, WILLIAM H. McCOY and A. WHEELER, of Charlestown, in the county of Middlesex, and State of Massachusetts, have invented an improved Stocking-Band or Supporter; and we do hereby declare that the following, taken in connection with the drawings which accompany and form part of this specification, is a description of our invention sufficient to enable those skilled in the art to practise it.

In the employment of the ordinary flexible garter, for securing a stocking in place, annoyance, pain, and injury are often caused to the wearer by the garter acting as a ligature, and stopping the free circulation of blood through the leg, and various devices have been employed to remedy this evil, none of which, however, so far as we know, have been practically efficient. Our invention relates to the construction of a band or stocking-supporter, which, while holding the stocking securely in position, shall not unduly press upon the leg, and the invention consists in an inelastic band made in two parts, hinged together, so that the band may be opened and shut, to readily apply it to and close it around the leg, the stocking being drawn over this band, when so closed upon the leg, and being confined to the concave outer surface of the band by an elastic or garter.

The drawings represent a band or stocking-supporter embodying the invention.

A and B show side and edge views of the same.

C is a section, taken on the red line seen in A and B.

The band is shown as made of metal, in two parts, *a*, *b*, hinged together at *c*, so that the parts may be opened to place the band around the leg. At its end opposite to the hinge the piece *a* has two ears or bearings, *d*, supporting a cross-pin or clamp-wire, *e*, and between this clamp-wire and the end of the piece *a* the adjacent end of the piece *b* is slid when the band is applied. The clamp-wire has a bend, *f*, as seen at D, and on its end it carries a handle, *g*, for turning it. The end of the band which slides under the clamp is provided with a series of depressions or grooves, *h*, and when any one of these is brought under the shaft and the clamp-wire is turned down towards it, said wire enters the groove and secures the piece *b* from slipping movement relatively to the piece *a*, or secures the two parts firmly together, while, by turning the shaft outwardly, the end of *b* may be slipped freely, in either direction, under the shaft.

Instead of applying this band around the stocking, as is done with a common garter or elastic, the band is first applied to the leg, and the stocking drawn up over it. Then an elastic or garter is wound and fastened around the stocking, against the band, the stocking and elastic sinking into the depression in the band, as will be readily understood. It will thus be seen that the band may be easily applied and removed by opening the parts *a*, *b* on their hinge, and that, when adjusted sufficiently tight around the leg, the free ends may be secured together in such manner as to hold and support the stocking securely in position, or without any liability of its slipping from or with the band, while the inflexibility of the band, as regards any short section or portion of its length, prevents it from so binding upon or against the surface of the leg as to obstruct the free and proper circulation of blood. Small spurs or teeth, or any equivalent eccentric projection, may be placed upon the clamp, instead of the bend in the wire, but we consider the bend as generally preferable.

Holes *i* may be provided along the band for stitching thereto the material with which the band is generally to be covered, and the band is preferably made with a slight inward convexity, as seen at B and C, for keeping the edges from bearing against the leg. The band may be made of metal, or of hard rubber or other similar inflexible material. For cheapness and efficiency we have found zinc to answer the purpose very well.

We claim the stocking-band or supporter *b*, when made in two parts, hinged together at *c*, substantially as described.

We also claim the clamp-wire *g*, having a bend or eccentric *f*, working in combination with the grooves *h*, to fasten the band, substantially as shown and described.

WM. H. McCOY.
A. WHEELER.
